UNITED STATES PATENT OFFICE.

JACOB R. ETTER, OF CRAWFORDSVILLE, INDIANA.

INSTRUMENT FOR TRANSMITTING AUDIBLE TIME-SIGNALS.

SPECIFICATION forming part of Letters Patent No. 357,310, dated February 8, 1887.

Application filed April 12, 1886. Serial No. 198,654. (No model.)

To all whom it may concern:

Be it known that I, JACOB R. ETTER, a citizen of the United States, residing at Crawfordsville, in the county of Montgomery and State of Indiana, have invented a new and useful Improvement in Automatic Time-Signals, of which the following is a specification.

My invention relates to an improved machine for transmitting time-signals from a central or principal office of a railroad company to a series of stations along its road by means of the ordinary electric telegraph-line and the receiving-instruments used in the transmission of messages.

15 The object of my improvement is to provide a simple mechanism for automatically opening and closing a normally-closed electric circuit, thereby giving simultaneously at each of a series of stations connected with said circuit two distinct kinds of signals—the first being a call-signal to attract the attention of the operators, and the second being a time-signal—said mechanism being connected with and controlled by a time-piece located near the 20 machine, all as hereinafter fully described.

The accompanying drawings illustrate my invention, Figure 1 representing a side elevation of a time-piece and my machine and a series of stations. Fig. 2 is a plan of the machine.

A is a frame having suitable bearings, in which are mounted so as to revolve the shafts b and c. On shaft b are secured the gear-wheel d, the stop-wheel e, carrying cams f and g, and the drum h. On shaft c are secured the pinion i, which intermeshes with the gear-wheel d, and the signal-wheels j and k. The periphery of wheel j is provided with a series of projections, m, regularly arranged, and the 35 periphery of wheel k is provided with a series of depressions, n n, of unequal length, and preferably arranged relatively to correspond to portions of the Morse code of telegraphic signals. Those shown in the drawings represent the Morse signals for the figure 12.

B and C represent opposed terminals of the electric circuit l, in which are a series of stations. Terminal B is secured to a fixed support, o, forming a part of the frame A. Terminal C is secured to a lever, p, which is rigidly secured to the shaft r, which is arranged

to slide longitudinally in bearings formed in the frame A. One end of lever p is adapted to engage either of the signal-wheels, the arrangement being such that both of said wheels 55 cannot be engaged by the lever at the same time.

The terminals B and C are held normally in contact, so that the electric circuit is closed, by the spring t. Shaft r is caused to slide in 60 its bearings, and the position of lever p is thereby changed, so that its inner end will engage the wheel k and be disengaged from the wheel j by means of the lever D, which is pivoted to the frame at u. One end of said 65 lever engages a pin, v, projecting from the shaft, and the other end engages either of the cams f and g as wheel e revolves. Lever D is held by the spring s against the side of wheel e in the path of cams f and g, so that lever p 70 engages wheel j.

Motion is imparted to shaft b and the wheels connected therewith by means of a weight (not shown) suspended from the drum h, or by a spring coiled thereon. Said shaft and its 75 connected wheels are held at rest by the locking-wire E, which engages the notch w in wheel e. Locking-wire E is raised and thereby disengaged from wheel e by means of a lever, F, mounted in the clock H and arranged 80 to engage the cam-wheel x, which is mounted on the hour-hand shaft of the clock, so as to revolve therewith in the manner usual in alarm-clocks. Lever F and pawl E are connected by a rod or cord, y.

85 The operation of my device is as follows: The machine being at rest, the lever p rests on the periphery of the signal-wheel j, and terminals B and C are in contact. The circuit being unbroken at the point where the machine is introduced, communication over the line goes on as usual until the circuit is broken by the lifting of lever p. This is arranged to occur, as shown in the drawings, when the clock indicates the hour of twelve; but it may 90 be arranged to occur at any hour desired by turning the cam-wheel x on the hour-hand shaft. At this point the inner end of lever F falls and locking-wire E is raised, thereby releasing shaft b and the train of gears connected 95 therewith. Wheels d and e turn in the direction indicated by the arrow, and the signal-

wheels *j* and *k* are revolved in the opposite direction. As wheel *j* revolves, the projections *m* operate to raise the lever *p*, and thereby open and close the circuit at regular intervals, 5 thus calling the operator at each station along the line. When the wheel *e* has nearly completed a half-revolution, cam *f* engages the switch-lever *D*, thereby shifting lever *p* from wheel *j* to wheel *k*, and the Morse signal "12" 10 is then given, being repeated until the wheel *e* has completed its half-revolution, when locking-wire *E* again falls into a notch like *w* in the wheel, and the line is restored to its normal condition.

15 I claim as my invention—

1. In an automatic signaling apparatus, the combination of a train of gear-wheels and shafts mounted in a suitable supporting-frame, two wheels having each a series of peripheral 20 projections differently arranged on the two wheels and mounted side by side on one of said shafts, so as to revolve therewith, a lever carrying one of the terminals of a normally-closed electric circuit and arranged to engage 25 the projections on either of said wheels, a cam-wheel arranged to revolve with said train

of gear-wheels, and a switching mechanism arranged to engage said cam-wheel and to be actuated thereby, and connecting with the lever carrying one of the terminals of the 30 electric circuit, whereby said electric circuit is alternately made and broken, first at regular and then at irregular intervals of time, substantially as and for the purpose specified.

2. In an automatic signaling apparatus, 35 shafts *b* and *c*, gear-wheel *d*, and pinion *i*, wheel *e*, having notch *w*, wheel *j*, having projections *m*, lever *p*, terminals *B* and *C*, and spring *t*, all combined and arranged to co-operate in the manner and for the purpose specified. 40

3. In an automatic signaling apparatus, shafts *b* and *c*, gear-wheel *d*, pinion *i*, signal-wheels *j* and *k*, and lever *p*, switching-lever *D*, sliding shaft *r*, spring *s*, and wheel *e*, having cam *f*, all combined and arranged to co-operate in the manner and for the purpose specified. 45

JACOB R. ETTER.
